United States Patent

Des. 242,224
Patented Nov. 9, 1976

242,224

BOTTLE OR SIMILAR ARTICLE

Salvatore Ruriani, Elmira, N.Y., assignor to Lever
Brothers Company, New York, N.Y.

Filed May 8, 1975, Ser. No. 575,763

Term of patent 14 years

Int. Cl. D9—01

U.S. Cl. D9—149

FIG. 1

FIG. 2

FIG. 3

FIG. 4

FIG. 5

FIG. 1 is a front elevational view of a bottle showing my new design;

FIG. 2 is a side elevational view thereof;

FIG. 3 is a top plan view thereof;

FIG. 4 is a bottom plan view thereof; and

FIG. 5 is a top perspective view showing the front and one side thereof.

I claim:

The ornamental design for a bottle or similar article, substantially as shown.
